UNITED STATES PATENT OFFICE.

JOESEPH LEVIN, OF BALTIMORE, MARYLAND.

DESIGN FOR A SUPPORTING-CROWN FOR PARASOLS.

56,668.

Specification for Design.

Patented Nov. 23, 1920.

Application filed October 6, 1919. Serial No. 328,916. Term of patent 3½ years.

To all whom it may concern:

Be it known that I, JOESEPH LEVIN, a citizen of the United States of America, residing at Baltimore, in the State of Maryland, have invented a new, original, and ornamental Design for a Supporting-Crown for Parasols, of which the following is a specification, reference being had to the accompanying drawing, forming part thereof.

In the drawing,
Figure 1 is a side elevation of the supporting crown, and
Fig. 2 is a bottom plan view thereof.

I claim:
The ornamental design for a supporting crown for parasols as shown.

JOESEPH LEVIN.
